UNITED STATES PATENT OFFICE.

JARED A. AYRES, OF MYSTIC RIVER, CONNECTICUT, ASSIGNOR TO THE
PNEUMATIC ENGINE COMPANY, OF SAME PLACE.

BOILER FEED-WATER APPARATUS.

SPECIFICATION forming part of Letters Patent No. 274,103, dated March 20, 1883.

Application filed June 21, 1882. (No model.)

To all whom it may concern:

Be it known that I, JARED A. AYRES, of Mystic River, in the county of New London and State of Connecticut, have invented certain new and useful Improvements in Boiler Feed-Water Apparatus, of which the following is a specification.

My invention relates to automatic means for controlling the supply of water to the boiler, so that without the care of an attendant a practically even quantity may be kept therein; and it consists in combining with the boiler a supply-pipe leading to a closed water-box below the level of the water therein, a continuously-driven air-forcing pump, delivering by pipe to said box, a blow-off hole or tap between said pump and the water-box, and means automatically controlled by the increase or diminution of the water in the boiler for opening and closing said hole or tap to intermit or insure the supply of compressed air to said box; in combining with the boiler and the closed water-box from which it is supplied a continuously-driven air-forcing pump, communicating by pipe with said box to deliver compressed air thereto, a blow-off hole between said pump and box, a valve to close said hole, and a lever automatically controlled by the rise and fall of the water in the boiler to open and shut the valve, thereby stopping or starting the supply; in combining with the boiler and the closed water-box from which it is supplied a continuously-driven air-forcing pump, communicating by pipe with said box to deliver compressed air thereto, a blow-off hole between said pump and box, a valve to close said hole, and a water case or cylinder connected with one arm of said lever supplied freely from the boiler, so that the water-level in the two shall be the same and rising and falling limitedly with the fluctuations of its contents, whereby the lever is operated; in combining with the boiler and the lever which controls the water-supply pump a water case or cylinder connected with said boiler and supported therefrom by an elastic supply-pipe, so that it will sink or rise with the fluctuations of water-level and move the lever; and in the various other combinations and details of construction, hereinafter described and claimed.

In the drawings, Figure 1 is a side elevation, partly in section, of mechanism embodying my invention. Figure 2 is a plan view of the same.

A is any boiler connecting by steam-pipe *a* with a small engine, B—for instance, an oscillating engine—which, by means of pitman or piston rod *b* and crank *b'*, drives a shaft, C, provided with a fly-wheel, *c'*, for the usual purpose. A second crank, *c'*, upon this shaft operates through pitman *d* the piston of an air-forcing pump, D.

Engine, shaft, and pump are herein shown as mounted upon a common base-plate, E, which forms the cover to a tank or hot-well, F, into which the exhaust-steam from the engine is discharged by pipe *f*, thus keeping the contents at a high temperature. This arrangement is compact and desirable; but any other may be adopted.

Within the tank or hot-well, and near to its bottom, is placed a closed water-box, G, receiving its supply from the tank through clack-valve *g* in its own bottom. From this water-box an education-pipe, H, leads to the boiler, a check-valve, *h*, at some suitable point inhibiting retrograde flow of the feed-water passing therethrough.

An air-pipe, I, leads from the air-forcing pump to the top of the water-box to conduct the compressed air thereto, and intermediate between the pump and box has a branch, *i*, which terminates, as at *i'*, in a tap or blow-off hole formed with a valve-seat. One arm of a lever, K, overhangs this blow-off hole, carrying a valve, *k*, to close it. The valve-arm of the lever is in the present instance and preferably drawn down by the stress of a spring, *k'*, so that the valve tends constantly to shut against its seat in the blow-off hole. It is, however, feasible, by a slight change of mechanism—such as will be readily apparent from the ensuing description—to reverse the action of the spring, causing it to press the valve open. It is evident now that if the valve-arm of the lever is down, and the blow-off hole consequently closed, the compressed air from the air-forcing pump will be driven into the water-box, and will force its contents out through the education or boiler-feed pipe into the boiler; but if the free arm of the lever is depressed, carrying the valve away from the blow-off hole

and opening the latter, the stream of air will escape therethrough, the pressure in the water-box be relieved, and the latter consequently be refilled from the surrounding tank.

5 In a previous application filed by me in the Patent Office of the United States on the 15th day of June, 1882, of which the construction thus far described, with immaterial variations as to the manner of its exposition, is made the special subject-matter, the opening and closing of the blow-off hole is proposed to be accomplished by any suitable means, whether manual or automatic. In the present case the motions of the lever are to be caused and determined at the proper times by automatic means, governed by the decrease and increase of the water-supply within the boiler—such, for instance, as the rise and fall of the boiler itself, as described in another application filed 10 by me on the 7th day of December, 1881—or a float resting upon the surface of the water in said boiler, or other appropriate instrumentality. A simple mode, however, and one equally applicable to actuating the lever or equivalent mechanism when used for stopping and starting a different form of feed-pump, is as follows:

A small closed cylinder, M, of brass or other suitable metal, is mounted exteriorly to the boiler in manner similar to a water-gage, except that the pipes m m' , which connect it to said boiler at top and bottom, form its sole means of support therefrom, and are coiled and of sufficient length to afford some elasticity and allow the cylinder to make a slight rise and fall, according to the amount of water it contains. The fluctuations of level in this cylinder will correspond to the fluctuations in the boiler and its elastic supplying and supporting arms. A short arm or offset, m^2 , from 30 the cylinder carries a ring or yoke, m^3 , which takes over the free arm of the valve-lever. Supposing the water in the boiler to be low, the cylinder will be light and rise, permitting the valve to close by the stress of the spring, 35 when feed will immediately commence. As the water rises in the boiler the cylinder becomes heavy and sinks, depressing the free arm of the lever and throwing the valve open, thereby again stopping the feed. I do not 40 confine myself to the use of this rising and falling cylinder and its elastic supplying and supporting arms with the specific form of pump above described, since it is evident, as already intimated, that it may be made to actuate through 45 the lever a stop-cock in a feed-pipe supplied from an overhead reservoir, or in a steam-pipe leading to some other form of pumping mechanism, or a clutch or shipper for starting and stopping such pumping mechanism; nor do I

confine myself to said cylinder as the sole and only means of automatically controlling the opening and closing of the blow-off hole in the described novel pump, considering it, however, preferable to others hereinbefore suggested.

A rising and falling water case or cylinder, 60 connected with the boiler by flexible pipes and supported upon a weighted lever, has heretofore been caused to actuate the arm which controls the water-supply, and in another instance a cylinder supported from the boiler by elastic 65 pipes has served as a water-gage, but as nothing else. These are readily distinguishable from the device proposed by me, and I lay no claim to them or either of them; but

What I do claim is—

75 1. In combination with a boiler, a supply-pipe leading to a closed water-box, a continuously-driven air-forcing pump delivering by pipe to said box, a blow-off hole or tap between said pump and water-box, and means automatically controlled by the increase or diminution of the water in the boiler for opening and closing said hole or tap to intermit or insure the supply of compressed air to said box.

2. In combination with a boiler and a closed 80 water-box, from which it is supplied, a continuously-driven air-forcing pump communicating by pipe with said box to deliver compressed air thereto, a blow-off hole between said pump and box, a valve to close said blow-off hole, 85 and a lever automatically controlled by the rise and fall of the water in the boiler to open and shut the valve, thereby stopping and starting the feed.

3. In combination with a boiler and a closed 90 water-box from which it is supplied, a continuously-driven air-forcing pump communicating by pipe with said box to deliver compressed air thereto, a blow-off hole between said pump and box, a valve to close said hole, a lever controlling said valve, and a water case or cylinder connected with one arm of said lever supplied freely from the boiler, so that the water-level in the two shall be the same, and rising 95 and falling limitedly with the fluctuations of its contents, whereby the lever is operated.

4. In combination with the boiler and with the lever which controls the feed-pump or water-supply, a water case or cylinder connected with said boiler and supported therefrom by an elastic supply pipe or pipes, so that it will sink or rise with the fluctuations of water-level and move the lever.
